Primary Examiner — Karen S Acker(74) *Attorney, Agent, or Firm* — Sughrue Mion, PLLC(57) **CLAIM**

The ornamental design for a lenticular lens sheet, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a lenticular lens sheet;
FIG. 2 is a perspective view thereof viewed from diagonally forward right with respect to FIG. 1;
FIG. 3 is a perspective view thereof viewed from diagonally forward left with respect to FIG. 1; and,
FIG. 4 is a rear view thereof.
The appearance of the design changes in accordance with the direction in which the article is viewed.

1 Claim, 4 Drawing Sheets
(4 of 4 Drawing Sheet(s) Filed in Color)
